UNITED STATES PATENT OFFICE.

JOHN H. DOFFING, OF NEW TRIER, MINNESOTA.

ROLLING COLTER.

1,413,709.

Specification of Letters Patent. Patented Apr. 25, 1922.

Application filed March 25, 1920. Serial No. 368,807.

To all whom it may concern:

Be it known that I, JOHN H. DOFFING, a citizen of the United States, residing at New Trier, in the county of Dakota and State of Minnesota, have invented certain new and useful Improvements in Rolling Colters; and I do hereby declare the following to be a full, clear, and exact description of the invention, such as will enable others skilled in the art to which it appertains to make and use the same.

This invention relates to new and useful improvements in rolling colters, and has for its primary object the provision of a mounting for the colter which normally urges the colter into or in the direction of the ground, but will permit the colter to swing upwardly when engaging an obstruction thereby permitting the plow to remain in the ground and not cause it to move outwardly therefrom which allows better and even plowing and also reduces to a great extent the dulling of the colter caused by striking rocks and having to raise the weight of the plow thereafter.

Another object of this invention is the provision of means which permits the colter to oscillate about a vertical axis so that said colter may more readily follow the path of travel and keep in front of the plow point.

A further object of this invention is the provision of a rolling colter of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:—

Figure 1 is a side elevation illustrating a rolling colter attached to a plow and constructed in accordance with my invention and also illustrating the colter in dotted lines occupying a position caused by engaging an obstruction,

Figure 2 is a perspective view illustrating a clamp to be secured to the plow beam, 55

Figure 3 is a similar view illustrating a journal for the colter standard,

Figure 4 is a similar view illustrating the colter hanger,

Figure 5 is a plan view of the supporting 60 shaft or standard.

Referring in detail to the drawing, the numeral 1 indicates as an entirety a plow including a plow beam 2 having the usual plow share 3 at one end and the plow handles 4. The foregoing description relates to a well known construction of plow to which my invention is applicable.

A hanger 5 consists of a tubular portion 6 on which is formed relative spaced arms 7. 70 The arms 7 have journalized therebetween the colter or disk 8. A standard or supporting shaft 9 has one end disposed in the tubular portion 6 and is secured therein by a set screw 10 which is carried by said standard 75 and extends through a slot 11 in said tubular portion to permit the hanger 5 to swing about a vertical axis.

A plate 12 is secured to the plow beam adjacent its forward end by means of a substantially U-shaped clamp 13 and said plate has formed thereon a right angle extending bolt 14. A sleeve 15 is rotatably secured on the bolt 14 by means of a nut 16 and has formed integrally therewith a collar 17 85 which receives the upper portion of the standard or supporting rod 9. The collar is secured to the standard or supporting rod 9 by a set screw 18 providing a construction wherein the standard or supporting rod can 90 be adjusted in relation to the clamp. A collar 20 is secured to the upper end of the standard or supporting rod by means of a set screw and has one end of a coil spring 21 secured thereto, while the other end of the 95 coil spring has attached thereto an eye bolt 22 which is adjustably secured to the rear portion of the plow beam 2.

The standard or supporting rod 9 is offset as illustrated at 23 so as to position the disk 100 or colter 8 in front and in alinement with the plow point of the plow share so that said colter will sever or cut roots, vines and other fragile objects that may be on the ground or partially imbedded in the ground. The disk 105 or colter 8 is normally urged in the direc-

tion and in engagement with the ground by the spring 21 and when said colter engages an obstruction such as a stone or log resting on the surface of the ground or partially 5 embedded in the ground, said colter swings upwardly against the tension of the spring permitting the plow to remain in the ground while the colter rides over the obstruction. By permitting the colter to swing upwardly 10 when engaging an obstruction, it relieves the dulling effect on the colter as well as permitting the plow to remain in the ground so that evener plowing can be accomplished.

It is also to be noted that the hanger 5 15 can swing about a vertical axis so that the colter or disk 8 will more readily follow the line of travel.

While I have shown and described the preferred embodiment of my invention, it 20 will be understood that minor changes in construction, combination, and arrangement

of parts may be made without departing from the spirit and scope of the invention as claimed.

Having thus described my invention, what 25 I claim is:

In a colter, a substantially horizontal spindle, a sleeve journaled on the spindle, a substantially vertical sleeve integral with said first sleeve, a standard adjustably secured in said second sleeve for axial and longitudinal movement having an offset end, a colter, a colter hanger extending from said end, and a spring associated with the standard to urge the colter into contact with the 30 ground.

In testimony whereof I affix my signature in presence of two witnesses.

JOHN H. DOFFING.

Witnesses:

A. MUELLERLEILE,
ARTHUR HOFFMAN.
